ATTORNEY

UNITED STATES PATENT OFFICE.

RALPH F. THACKSTON, OF ANDERSON, SOUTH CAROLINA.

ROCKER-SHAFT BEARING.

1,374,779.

Specification of Letters Patent.

Patented Apr. 12, 1921.

Application filed May 29, 1920. Serial No. 385,320.

To all whom it may concern:

Be it known that I, RALPH F. THACKSTON, a citizen of the United States, residing at Anderson, in the county of Anderson and State of South Carolina, have invented new and useful Improvements in Rocker-Shaft Bearings, of which the following is a specification.

This invention relates to attachments for 10 looms, and has for its object the provision of a novel bearing having a socket in which is removably mounted a wooden block curved for engagement with the picker foot, the socket being adapted to contain oil which 15 will be drawn through the wooden block by capillary action for effecting thorough lubrication.

An important object is the provision of a bearing of this character which is adapted 20 to support the picker foot properly so as to effect the making of a steady pick, another feature being that the bearing is adjustable whereby to take up all lost motion.

An additional object is the provision of a 25 device of this character which will be simple and inexpensive in manufacture, a great time and labor saver, which will be efficient and durable in use, and a general improvement in the art.

With the above and other objects and advantages in view, the invention consists in the details of construction to be hereinafter more fully described and claimed, and illustrated in the accompanying drawings in 35 which—

Figure 1 is an elevation of the device in position upon a portion of a loom,

Fig. 2 is a plan view,

Fig. 3 is a cross sectional view there- 40 through, and

Fig. 4 is an elevation of the device de- tached and looking at the rear face.

Referring more particularly to the drawings, the letter A designates the rocker bearing 45 of a loom, B designates a rocker shaft, and C designates the picker foot. The bearing is held on the loom by bolts D.

In carrying out my invention I provide a frame 10 including spaced upstanding por- 50 tions 11, each having a rectangular opening 12 formed therein. At the upper end of each portion 11 is a lateral projection 13 through which is threaded a vertical set- screw 14 carrying a lock nut 15. The device 55 is positioned against the rocker bearing A with the bolts D passed through the open-

ings 12. The projections 13 are disposed over the upper edge of the bearing with the set-screws engaging said upper edge. The frame 10 further includes a pan or socket 60 portion 16 which extends laterally therefrom at the side opposite the projections 13 and this pan is adapted to contain oil. Removably disposed within the pan 16 is a block 17 of hard wood having the grain 65 extending vertically and having its tip grooved, as shown at 19, for engagement with the picker foot C. The groove 19 forms the bearing surface upon which the picker foot rocks and it will be observed that 70 owing to the capillary action of the wood of the block 17, the oil within the pan will be drawn through the block, saturating it and will efficiently lubricate the bearing surface engaged by the picker foot. 75

When the device is constructed as above described and mounted upon a loom, it becomes a part of the loom and incidentally does not require any alterations in the loom structure. When the block 17 becomes worn 80 slightly, it will be observed that any lost motion in the moving parts may be taken up by adjusting the set screws 14. When the block 17 becomes badly worn it is obvious that it may be readily replaced at trifling 85 cost so that my bearing structure is very economical as well as simple.

While I have shown and described the preferred embodiment of my invention, it is of course to be understood that I reserve the 90 right to make such changes in the form, construction, and arrangement of parts as will not depart from the spirit of the invention or the scope of the subjoined claims.

Having thus described my invention, I 95 claim:

1. A device of the character described comprising a frame including spaced up- 100 standing portions each formed with a lateral projection engageable upon the rocker bearing of a loom, set screws passing downwardly through said projections, each of said upstanding portions having formed therein a rectangular opening for the pas- sage of bolts holding the bearing to the loom, 105 a pan member projecting over one side of said frame and adapted to contain oil, and a wooden bearing block disposed within said pan and adapted to support the picker foot.

2. In combination with a loom and the 110 picker foot thereof, a bearing member comprising a supporting bracket vertically ad-

justably connected with the loom frame and formed with a pan-like projection extending from one face thereof, and a body of absorbent material disposed within said pan and 5 engaging the picker foot.

3. In combination with a frame and picker foot of a loom, the bearing device comprising a bracket structure secured against one face of said frame and provided

with means whereby to effect vertical adjustment, a pan-like projection formed integrally upon and projecting from one face of said bracket structure, and a block of wood disposed within said pan and engaging the picker foot whereby to form a bearing there- 10 for.

In testimony whereof I affix my signature.
RALPH F. THACKSTON.
